UNITED STATES PATENT OFFICE

160,268

CLOCK DIAL

Jack Meltzer, New York, N. Y.

Application May 25, 1949, Serial No. 2,887

Term of patent 7 years

(Cl. D42—10)

To all whom it may concern:

Be it known that I, Jack Meltzer, a citizen of the United States, residing in the city of New York, county of Bronx, and State of New York, have invented a new, original, and ornamental Design for a Clock Dial, for which the following is a specification, reference being had to the accompanying drawing, forming part thereof.

Fig. 1 is a top plan view of a clock dial embodying my design.

Fig. 2 is a side elevational view thereof.

Referring to Fig. 1, the Chinese symbols inside of the circular elements of the design are lined for color as follows: January—garnet red; February—amethyst purple; March—aquamarine blue-green; April—white; May—emerald green; June—white; July—ruby red; August—yellow-green; September—sapphire blue; October—lav-

ender; November—pale yellow; December—light blue.

I claim:

The ornamental design for a clock dial, substantially as shown and described.

JACK MELTZER.
